[57] **CLAIM**

The ornamental design for a tropic traveler shirt, as shown and described.

DESCRIPTION

FIG. 1 is a front elevational view of a tropic traveler shirt showing my new design with inwardly tilting upper pocket with snap element and outwardly tilting lower pockets; FIG. 2 is a rear elevational view thereof showing vents at the sleeves, side vents with opposing snap elements, vents at cuffs with snap elements on the cuffs and small loop at center of horizontal seam;

FIG. 3 is a top right front perspective view thereof;

FIG. 4 is a top right rear perspective view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines shown on the pockets are understood to represent conventional stitching.

Line shading shown at the side vents, at the sleeve vents and at the cuff vents are understood to represent openings in the shirt.
